[57] CLAIM

The ornamental design for connector for picture frames
or the like, as shown and described.

DESCRIPTION

FIG. 1 is a top plan view of a connector for picture
frames or the like showing my new design, the portion
of a picture frame being shown in broken lines for illus-
trative purposes only;

FIG. 2 is a side elevational view thereof;

FIG. 3 is an end elevational view thereof;

FIG. 4 is a bottom plan view thereof.

FIG. 1

FIG. 2

FIG. 3

FIG. 4
